UNITED STATES PATENT OFFICE.

IGNATZ GONYK, OF LJUBLJANA, YUGOSLAVIA.

BOLT LOCK.

Application filed February 16, 1927, Serial No. 168,701, and in Germany June 17, 1926.

My invention relates to slide bolt locks for large doors such as used in storage rooms, railway-cars and the like, and consists in a slide-bolt carrying the lock proper 5 that may at the same time serve as a handle for the bolt and it has particularly for its object to lock the slide-bolt as well in the locking position as in the open position which may in some cases be desirable. Fur- 10 ther objects of my invention will appear from the following specification.

In the accompanying drawing an embodiment of the invention is illustrated by way of example.

Fig. 1 is a front view of the locking device;

Fig. 2 shows a section through the slide bolt along line A—B of Fig. 1;

Fig. 3 illustrates the base plate for the 20 slide bolt in plan view;

Figs. 4 and 5 show on an enlarged scale the bolt seen from below in the closed and open position, respectively;

Fig. 6 shows the lock after removal of 25 the coverplate and annular locking member from below;

Figs. 7 to 14^a show various details; and

Fig. 15 illustrates the key used (Figs. 9 to 15 being drawn on an enlarged scale).

On the door 1 there is fastened by means 30 of screws 4 a base-plate 2 for carrying a slide-bolt 3. Said slide-bolt 3 is provided with a lock-casing 5 which serves as a handle. Longitudinal slots 6 are provided in the slide-bolt to receive bail-shaped guide elements 7 fastened to the door by means of screw bolts 8 having flat T-shaped heads 9 (Fig. 8) which engage with or fit into corresponding holes of the side parts of the 35 bail-shaped guide elements which extend through the slots 6. The screw bolts 8 extend through holes in the base plate 2 and through holes of the door upon which the slide bolt is mounted and are fastened by 40 means of nuts 10. In a similar manner the socket or keeper 12, with which the slide bolt engages in the locking position, is fastened by means of screw bolts 8 with flat T-shaped heads 9 and by means of nuts 10 on 45 the fixed door frame 11. On the T-shaped heads 9 holding the socket or keeper a little square plate 13 is laterally fastened by soldering which covers the side opening of the T-shaped slot of the respective wall of the 50 keeper and serves as a guide and at the 55

same time as a stop for the bolt end entering into the keeper. Beneath the screw bolts 8 the respective parts of the door are provided with washers 14 and 15 and between the frame 11 of the door and the keeper 12 a 60 plate 17 is fastened by means of a screw 16 which is in alignment with and forms a continuation of the base plate 2 upon which the bolt mechanism is mounted.

The cylindrical lock casing 5 is integral 65 with the bolt proper and constitutes together with the key 19 when put into the key-hole 18 a convenient handle for sliding the bolt into its keeper 12 or for withdrawing it therefrom. The lock is preferably of 70 the well known type of cylinder lock, in which a cylinder 20 may only be turned when all combination elements 21 have been brought into a certain position by means of the key 19. The combination elements 21 75 (Figs. 14 and 14^a) are of annular shape and are considerably smaller than the lock casing 5; they are provided with springs 22 on their outer side by means of which they abut against the inner wall of the casing 80 5 (Fig. 6). On the inner side they are provided with pins 23 and 24 arranged opposite to each other. The pins 23 of different combination elements are of different length so as to correspond to the respective steps 85 of the key-bit of a key 19 and extend through a hole 25 of an element 26 (Fig. 10) into the keyhole 18 of cylinder 20. The element 26 partly serves as a bearing for the cylinder 20 partly as a guide for the surrounding combination elements 21 and is fastened to the bottom of the lock casing 5 by means of screws 27. The pins 24 engage a groove 28 of the element 26 and some of them are provided with a cylindrical projecting portion 29 which is adapted to engage bores 30 of element 26 as well as bores 31 of cylinder 20. When the pins 23 engage the slot of the keyhole 18 the cylinder 20 90 cannot be turned. If, however, the key 19 is put into the keyhole 18 the steps of the key-bit press upon the respective pins 23 of the combination elements and move them backward so that the cylinder may be turned. If this back-pressing of the pins is 95 performed by means of a key not fitting the particular lock some of the combination elements 21 will be pressed back so far that the projections 29 engage with the bores 30 of element 26 and with bores 31 of cylinder 20, 100 105 110

the latter being again held against rotation. On the cylinder 20 an annular bolt fastener 32 is fitted from below (Figs. 4 and 12) having a projection 33 on the inner ring face which engages a longitudinal groove of the cylinder 20. Thus the bolt fastener will be moved with the cylinder 20 as soon as the latter is actuated by means of the key. The annular bolt fastener 32 moreover has 10 two lateral extensions 34, 35 (Fig. 12) arranged at a right angle relatively to each other. The extension 34 has an inclined upper face as shown in Fig. 13, while the extension 35 is provided with a downwardly 15 projecting lug 44. When the lock is in the open position projection 34 will occupy a position (Fig. 5), in which its axis is coincident with the longitudinal axis of the slide-bolt 3. When the lock is closed projection 35 will occupy this position (Fig. 4).

At the underside of the slide-bolt a recess 36 is provided extending approximately from the middle of the bolt to the lock casting 5 and in this recess a spring controlled 20 locking bar 38 is pivotally mounted on a cross pin 37 and controlled by a spring 39 which rests upon the base of recess 36. The bottom face of the locking bar 38 is provided with a protruding step 40 and its end which 25 extends towards the lock casing 5 forms a tongue 41 the lower face of which is inclined in the direction the lock is turned when actuated by the key. In the open position of the lock the inclined upper face of projection 34 of the annular bolt fastener 32 lies 30 below the inclined face of tongue 41 of the locking bar 38, the inclination of the upper face of projection 34 corresponding to the inclination of the lower face of the tongue 41. The locking element is thereby retained 35 against the action of its spring 39 in the recess 36 so that the step 40 of the locking bar 38 is raised above the upper face of the base-plate 2 upon which the bolt slides. 40 If the lock is closed and cylinder 20 together with the annular bolt fastener 32 is rotated in the direction of the arrow (Fig. 4) until its lug 44 meets tongue 41, the projection 34 will release the locking element 45 38 which under the action of spring 39 is pressed down. According to the position of the bolt at this moment—whether it has been drawn back or pushed forward—the protruding step 40 of the locking bar enters 50 into one of the two holes 42 of base-plate 2 which are arranged over corresponding recesses 43 in the door 1, and is held in this 55 position by projection 35, which by the turning of the key has been moved, so that it is 60 now bearing upon the upper face of tongue 41, thus preventing locking member 38 from being moved back into recess 36.

The slide-bolt may thus be locked not only in the closed position but also in the open 65 position which may be of advantage, if it

is desired to prevent accidental closing of a door, for instance in a storage house or railway car.

In some cases it may be convenient to 70 arrange the bolt in the fixed door frame and the keeper in the movable door.

What I claim is:

1. A locking bolt comprising a base plate having recesses therein, a bolt slidable on the plate, a locking bar pivotally mounted 75 in the bolt and movable out of the latter to engage a recess in the plate, and means carried by the bolt for swinging the bar on its pivot to move it into and out of locking engagement with the base plate.

2. A locking bolt comprising a base plate having apertures therein, a bolt slidably mounted on said plate and having a longitudinal recess formed therein, a locking bar pivoted at one end in said recess and having 85 a lug adjacent its free end for engaging said apertures, and a lock element for swinging the bolt into and out of locking position.

3. A locking bolt comprising a base plate, a bolt mounted on the latter having longitudinal slots formed therein, guide elements 90 in which the bolt is movable extending through the slots and through the base plate, and cooperating means on the base-plate and bolt for locking the latter in open and 95 closed positions.

4. A locking bolt comprising a base-plate having apertures therein, a bolt slidably mounted on said plate, a locking bar pivoted at one end in said bolt, said bar having a 100 tongue formed on its free end, and a lug adjacent said tongue for engaging said apertures, and a fastening element rotatably mounted on the bolt for engaging said tongue to raise the bar and thereby release 105 the lug from said recess.

5. A locking bolt comprising a base-plate having apertures therein, a bolt slidably mounted on said plate and having a longitudinal recess therein, a locking bar pivoted at one end in said recess, said bar having a tongue formed on its free end and a lug adjacent said tongue for engaging said apertures, a casing on the bolt, and an annular 110 actuating member rotatable in the casing and having lugs thereon for engaging said tongue to raise and lower the locking bar.

6. A locking bolt comprising a base-plate having apertures therein, a bolt slidably mounted on said plate, a locking-bar pivoted at one end in said bolt, and having a lug to engage said apertures, said bar having a tongue on its free end formed with an inclined lower face, a casing on the bolt and an annular actuating member rotatable in 115 the casing having a lug formed with an inclined upper face for engaging the lower face of said tongue.

7. A locking bolt comprising a base-plate having apertures therein, a bolt slidably 120

mounted on said plate and having a longitudinal recess formed therein, a locking-bar pivoted at one end in said recess and having a lug to engage said apertures, said bar 5 having a tongue on its free end formed with an inclined lower face, a casing on the bolt, an annular actuating member rotatable in the casing having a lug formed with an inclined upper face for engaging the lower face 10 of said tongue, said actuating member having an auxiliary lug to engage the upper face of the tongue to hold said bar in locked relation to the base plate.

8. A locking bolt comprising a base-plate 15 having apertures therein, a bolt slidably mounted on said plate, a spring pressed locking bar pivoted at one end in said bolt and having a lug adjacent its free end for engaging said apertures and an annular 20 actuating member rotatably mounted on said bolt and having radial lugs for alternately engaging the free end of the locking-bar for holding the latter in different positions.

25 9. A locking bolt comprising a base-plate having apertures therein, a bolt slidably mounted on said plate, a spring pressed locking bar pivoted at one end in said bolt, and having a lug adjacent its free end for 30 engaging said apertures, an annular actuating member rotatably mounted on said bolt and having radial lugs for alternately engaging the free end of the locking bar for holding the latter in different positions, and 35 mechanism for locking the actuating member.

10. A locking bolt comprising a base-plate having apertures therein, a bolt slidably mounted on said plate and having a longitudinal recess therein, a spring pressed locking-bar pivoted at one end in said recess and 40 having a lug to engage said apertures, said bar having a tongue on its free end formed with an inclined lower face, a casing on the 45 bolt, a cylinder mounted in the casing, a plurality of annular elements mounted on the cylinder, an annular actuating member mounted on the cylinder and having radial

lugs for alternately engaging the tongue for holding the locking bar in different positions. 50

11. A locking bolt comprising a base-plate having apertures therein, a bolt slidably mounted on said plate and having a longitudinal recess therein, a spring pressed locking-bar pivoted at one end in said recess and 55 having a lug to engage said apertures, said bar having a tongue on its free end, a casing on the bolt, a bearing element fixed in the casing, a cylinder mounted in the bearing element, a plurality of annular locking elements mounted on the cylinder, springs on the annular locking elements in frictional engagement with the casing, an annular actuating member mounted on the cylinder 60 and having radial lugs for alternately engaging the tongue for holding the locking-bar in different positions. 65

12. A locking-bolt comprising a base-plate having apertures therein, a bolt slidably 70 mounted on said plate and having a longitudinal recess therein, a spring pressed locking bar pivoted at one end in said recess and having a lug to engage said apertures, said bar having a tongue on its free end formed 75 with an inclined lower face, a casing on the bolt, a bearing element fixed in the casing, a cylinder mounted in the bearing element, a plurality of annular locking elements mounted on the cylinder and having pins 80 for engaging the bearing element and cylinder, springs on the annular locking elements in frictional engagement with the casing, an annular rotary actuating member mounted on the cylinder and having a radial lug 85 formed with an inclined upper face for engaging the lower face of said tongue to move the locking bar against the action of its spring, said actuating member having an auxiliary lug to engage the upper face of 90 the tongue to hold the locking bar in locked position.

In testimony that I claim the foregoing as my invention, I have signed my name.

IGNATZ GONYK.
